PROTECTIVE VISION DEVICE

David J. Crawford, United States Army, Durant, Miss., and Joseph M. Colby, United States Army, Lake Mills, Iowa

Application July 2, 1942, Serial No. 449,436

1 Claim. (Cl. 88—1)

(Granted under the act of March 3, 1883, as amended April 30, 1928; 370 O. G. 757)

The invention described herein may be manufactured and used by or for the Government for governmental purposes, without the payment to us of any royalty thereon.

This invention pertains to protectoscopes, and more particularly to means for protecting an observer stationed at an observation slit provided in an armored device including means for replacing an optical system therein which has been damaged.

An object of the invention is to provide an observation passage so formed as to reverse and eliminate projectiles which enter the observation passage.

Another object of the invention is to provide an optical system of brittle material which will shatter into numerous small particles when struck by a projectile and thereby facilitate easy removal from its mounting and permit a quick replacement.

Another object of the invention is to provide a protected, indirect observation sight for an armored device.

A further object of the invention is to provide a simple, rugged mounting which will enable an observer to remove quickly and conveniently a damaged optical system from an observation position.

The specific nature of the invention as well as other objects and advantages thereof will clearly appear from a description of a preferred embodiment as shown in the accompanying drawings in which:

Fig. 1 is a vertical section through a portion of the armored front of a device showing one embodiment of the optical system and its mounting.

Fig. 2 is a section on the line 2—2 of Fig. 1.

Fig. 3 is a rear view of the protectoscope in a tank door.

Fig. 4 is a sectional view showing the optical system support in the open position.

Fig. 5 is a vertical section of a rotary journal type protectoscope.

Fig. 6 is a sectional view on the line 6—6 of Fig. 5, and

Fig. 7 is a rear view of the rotary journal type protectoscope with a part broken away to show details of construction.

A vehicle or other device is equipped with protective armor plate 1. An observation slit 2 is provided in the armor plate. The split 2 preferably diminishes in size near the rear or interior of the plate 1 and then develops into an enlarged chamber 3 with an arcuate wall 4. The

wall 4 forms a cylindrically shaped bulge 5 with a hollow interior on the inner wall of the device. The lower portion 6 of this metal bulge 5 is pierced by a rectangular slot 7. A protectoscope 8 comprising a body portion 9 and a frangible 45° mirror system 10 attached thereto slides into the slot 7.

The armor plate 1, as shown in Figure 3, may be the door of a combat vehicle, having hinge 10 knuckles A and a suitable door operating mechanism B.

A support 11 is shaped to conform to the lower portion of the base of the protectoscope 8 and thereby hold it. The support 11 is carried by arms 12 which engage brackets 13 on the bulge 5 through pivot pins 14. Paralleling the rectangular slot 7 and at the rear of the support 11 is a longitudinal groove 15. A window 16 rests in this groove and is of sufficient height to engage the lower rear wall 17 of the bulge 5 when the support is in the closed position as shown in Fig. 1. This effectively seals the opening.

The front end 18 of the support 11 engages the under portion of the lip 19 of the protective armor 1. The lower edge of this front end 18 carries a groove 20 having angular sides and extends the length of the support. The armor plate 1 carries spaced brackets 21 beneath the front end of the support 11 and these brackets have hinge portions 22 which receive their complements 23 on a locking plate 24. The upper end of plate 24 is adapted to engage the groove 20 in the support 11 and hold the support in its closed position. Leaf springs 25 are attached at 26 to the ends of the plate 24 and are bent so that their free ends 27 rest in pressure engagement with the rear wall 28 of the armor plate. The springs 25 urge the plate 24 into engagement with the groove 20 of the support 11 and hold it in its locked position to maintain the protectoscope 8 in the operating position.

The observer is stationed with his eyes at the level of window 16 and his forehead may rest against a resilient bumper 29 which is cemented to the bulge 5. This protects his head from any jarring contacts.

The optical system comprises an integral or composite unit of brittle mirrors or prisms 10 which will burst into small pieces when hit by a projectile. Frangible plastics such as glass or Lucite have proved eminently satisfactory. Frangible reflectors 10 may be cemented to a periscope body 9 which is preferably constructed of a brittle transparent material. Frangible reflectors or a frangible optical system have a

decided advantage over polished metal reflectors. Metal elements are fractured by a projectile and become bent or distorted. This generally impairs the immediate removal of the damaged optical system since the recess 7 is smaller than the distorted and enlarged metal reflectors. Hence the employment of a frangible reflector or a frangible reflector and body increases the efficiency of an observation device from a military standpoint.

Another important feature of the invention is the configuration of the observation slit 2 and its connecting cavity 3. The smooth arcuate wall 4 forms a chamber having a shape in the nature of an elliptical cylinder which communicates at its lower portion with the rectangular slot 7. A projectile entering the observation slit 2 from any angle strikes the protecting wall 4, ricochets in the cavity 3 and is ejected by its own momentum through the entering slit 2. In its path the projectile shatters the brittle plastic reflecting system and the momentum imparted to these particles carries them against the deflecting wall 4 of the cavity 3 and eliminates them from the observation channel.

Pressure is applied to the plate 24 to overcome the resistance of leaf springs 25. This rotates the plate counterclockwise about its hinge 23 and removes the upper end of the plate from the groove 20 in the support 11. Support 11 is now free to rotate counterclockwise about the pivot pins 14 and drops open as shown in Fig. 4. The damaged optical system 8 falls out of its slot 7. A new system may be inserted and the gate support 11 swung into position and automatically latched by the spring pressed plate 24.

Fig. 5 delineates another embodiment in which the protectoscope 8 is mounted in a cylindrical rotor or journal 30. The journal 30 rotates in a suitable hollow bearing (not shown) in the protective armor. When the optical system 8 is destroyed by gunfire the journal is rotated counterclockwise until the hood or visor 31 seals the observation slit. The protectoscope 8 is removed

and a new one inserted whereupon the journal 30 is turned clockwise and the unit is again ready for action. This type of a protective vision device may be employed effectively near a gun port.

The construction of the protectoscope support 11 and its latching mechanism is similar to that shown in Fig. 1. For convenience in manufacturing the hinge arrangement for the plate 24 is altered slightly. A bracket 32 is fastened to the front wall 33 of the rotor 30 by screws 34. (See Figs. 5 and 6.) The bracket 32 is in the form of a bar which is somewhat shorter than the rotor and has a depending apron 35. The lower end of this apron is curved to form hinge members 36 which engage a shaft 37. Similar members on plate 24 complete the hinge and constitute the points about which the locking plate 24 oscillates. This bracket 32 eliminates the difficult machining and drilling of the thin fin 38 to receive a hinge and facilitates mass production. The springs 25 are attached to the plate 24 in the conventional manner and have their free ends 27 bearing on the bracket 32.

25 We claim:

30 A support for a periscope comprising a member having a substantially horizontal viewing aperture and a vertical aperture extending downwardly from said horizontal aperture adapted to receive a periscope, a hingedly connected support member having a recess for mounting the lower end of a periscope therein and for sealing off the bottom of said vertically extending aperture, a heavy window in said support member adapted to be in optical alignment with a periscope disposed in said vertical aperture and mounted in said recess of said hinged support member, and a manually releasable, spring urged locking member for locking said hingedly connected support member in sealing relationship with the bottom of said vertically extending aperture.

40 DAVID J. CRAWFORD.
